UNITED STATES PATENT OFFICE.

HENRY W. YOUNGQUIST, OF MANCHESTER, NEW HAMPSHIRE, ASSIGNOR TO DRAPER CORPORATION, OF HOPEDALE, MASSACHUSETTS, A CORPORATION OF MAINE.

SHUTTLE-CLEARING MEANS FOR FILLING-REPLENISHING LOOMS.

Application filed July 16, 1921. Serial No. 485,276.

To all whom it may concern:

Be it known that I, HENRY W. YOUNGQUIST, a citizen of the United States, and resident of Manchester, county of Hillsborough, State of New Hampshire, have invented an Improvement in Shuttle-Clearing Means for Filling-Replenishing Looms, of which the following description, in connection with the accompanying drawing, is a specification, like characters on the drawing representing like parts.

This invention relates to improvements in filling end clearing mechanism for automatic filling replenishing looms and the object is to provide an effective mechanism which will engage and clamp positively the filling end running from a discharged filling carrier so that the removal of said filling end from the shuttle will be insured.

In the operation of automatic filling replenishing looms the running filling is replenished from time to time by the insertion of a fresh filling carrier into the running shuttle and simultaneously ejecting therefrom the filling carrier from which the filling is more or less exhausted. When the old filling carrier is thus ejected from the shuttle a trailing filling end extends through the shuttle eye which must be removed in order to clear the shuttle eye for the fresh filling and also to prevent the trailing filling end from being carried by the shuttle into the shed.

I am aware that various means have been provided for clearing the filling end from the shuttle, such for example as that disclosed in Patent No. 812,516, Northrop, February 13, 1906.

The object of the present invention is to provide an improved mechanism for accomplishing this purpose comprising a filling end clamping means which will be opened during the initial action of the transferring mechanism before the lay beats up against the fell of the cloth and which will engage and clamp the filling end of the discharged filling carrier during the final portion of the movement of the transfer mechanism so that the filling end will be securely clamped before the shuttle is picked after transfer, thereby insuring the withdrawal of the old filling end from the shuttle eye and preventing with certainty the drawing of the filling end into the shed.

A further object of the invention is to

provide means for locking the filling end clamping means in closed position during the normal operation of the loom and means operable, preferably from the dog of the transfer mechanism, for unlocking and permitting the opening of the filling end clamping means as the dog is moved into operative position.

A further object of the invention is to provide means operated by the transfer mechanism to restore the filling end clamping means to locked position during the final movement of the transfer mechanism.

A further object of the invention is to provide yieldable means for actuating the filling end clamping means which will prevent breakage of said clamping means if any obstruction intervenes between the jaws of the clamping means.

A further object of the invention is to provide a novel form of clamping means comprising a stationary jaw extending in a direction normal to the longitudinal axis of the lay and having an end extending in parallelism with the axis of the lay, adapted to insure the catching of the filling end, with a movable jaw so mounted as to be moved transversely across the path of the filling end running from the shuttle to the discharged filling carrier.

Other objects and features of the invention will more fully appear from the following description and the annexed drawings and will be pointed out in the accompanying claims.

In the drawings:

Fig. 1 is a vertical sectional view, looking toward the hopper end of a loom, showing a sufficient portion of the loom to illustrate a preferred embodiment of the invention applied thereto;

Fig. 2 is a front elevation of the transferring mechanism of the loom illustrating the invention embodied therein;

Fig. 3 is a plan view of the same showing the filling end clamping means in closed position;

Fig. 4 is a detail plan view of the filling end clamping means illustrated in open position and the mechanism for actuating the same, the supporting brackets being shown in section; and,

Fig. 5 is a side elevation of the means for actuating the filling end clamping means illustrated in Fig. 4.

110

The present invention is designed to be embodied in or applied to a usual type of loom, such as the well known "Northrop" loom and only a sufficient portion of such a loom is illustrated herein as is necessary to show the application of the present invention thereto.

As illustrated herein the loom comprises the usual side frame 1 upon which is mounted the hopper stand 2 carrying the hopper 3 adapted to support a circular series of fresh filling carriers. The filling carriers are transferred from the hopper to the shuttle 4 which is carried by the lay 5 by a transferrer 6 having a head 7 adapted to engage the bases of the filling carriers, and force them from the hopper into the shuttle, thereby causing the incoming filling carrier to eject the old filling carrier from the shuttle. The transferrer arm 6 is pivotally mounted upon a transferrer stud 8 which is carried by the hopper stand 2 and is provided with a downward extension 9 on the lower end of which a dog-supporting member 10 is pivotally mounted which carries a dog 11 adapted upon transfer to be positioned in the path of the bunter 12 carried by the lay 5.

The dog 11 is provided with a stud 13 which engages a cam slot in the usual arm 14 which is connected to the shuttle feeler and is operated through an arm 15 upon the controller rod 16. The controller rod 16 may be actuated as is usual either by the feeler mechanism or the weft fork mechanism of the loom, or both.

The transferrer stud has secured to its end an arm 17 upon the end of which a holder 18 for the tip of the bobbin is yieldably mounted. The transferrer arm is also provided with a tip engaging member 19 which, upon actuation of the transferrer, engages the tip of the bobbin at the same time the transferrer head 7 engages its base. The member 19 thus serves to guide the tip of the bobbin during the transfer of the bobbin from the hopper into the shuttle.

The mechanism thus described may be and is a usual type of construction and, therefore, need not be further described.

The present invention contemplates the provision of novel means, preferably supported upon the transferrer stud, for catching and clamping the filling end from the ejected bobbin immediately after the bobbin has been discharged from the shuttle and positively holding the same until transfer is again called for. By reason of this construction the withdrawal of the trailing filling end from the shuttle eye is insured and the possibility of said trailing end being whipped into the shed is effectively prevented.

In the preferred embodiment of the invention the filling end clamping means com-

prises a bracket 20 which is secured at its upper end to the arm 17 of the tip supporting member and at its lower end is provided with an offset horizontal extension 21 forming the stationary jaw of the filling end 20 clamping means. The horizontal extension or stationary jaw extends in a direction normal to the longitudinal axis of the lay and is adapted to enter the usual cutaway portion of the lay which is located below the shuttle box.

The stationary jaw 21 desirably is provided at its end with an integral laterally extending portion or finger 22 which extends substantially in parallelism with the longitudinal axis of the lay and is adapted to prevent the filling from being thrown beyond the end of said stationary jaw.

The stationary jaw desirably is provided with a facing 23, of leather or other frictional material, adapted to co-operate with the movable jaw to more firmly engage the filling end.

The filling end clamping means comprises also a toothed movable jaw 24 adapted to co-operate with the stationary jaw 23, said movable jaw 24 preferably being pivotally mounted upon a stud 25 projecting upwardly from the elbow of the bracket 20. The movable jaw is provided with a laterally extending boss or arm 26 which is engaged by a preferably resilient member 27 which is curved at its opposite end and anchored to a stud 28 which may be adjustably mounted in the offset end 29 of an actuating lever 30. The actuating lever 30 is pivotally mounted upon a stud 31 carried by a bracket 32 which has upon its upper end a boss 33 which is mounted upon the transferrer stud and is secured rigidly in position upon said stud by set screws 34. A spring 35, engaging at one end upon the lever 30 and at its opposite end abutting against a boss 36 upon the bracket 32, normally tends to force the end of said lever, which is connected to the movable jaw, in a direction as to move the movable jaw of the clamping means to open position.

Means preferably are provided, however, for normally locking the jaw, during the operation of the loom, in closed position. As illustrated herein this is accomplished by a detent lever 37 which is pivotally mounted upon a screw or stud 38 carried by the bracket 32. One arm of said detent lever has a shoulder 39 which engages the lever 30. The other arm 40 of said lever is provided with a cam face 41 upon its underside. A spring 42, interposed between the arm 40 and an abutment 43 upon the stud 32, normally tends to force the detent into locking position so that when the lever 30 is moved in such a manner as to force the movable jaw into closed position the detent will automatically act to lock the lever 30 and re-

tain the movable jaw in such closed position. Thus the clamping means may be held in closed position during the normal operation of the loom.

5 Suitable means are provided for unlocking the detent from its engagement with the lever 30 upon call for transfer. In the preferred embodiment of the invention illustrated herein the dog carrying member 10 is 10 provided with a laterally extending releasing arm 44 which has an offset lower end 45 which underlies the extension 40 of the detent. When the dog is actuated, upon call for transfer, the pivotal upward movement of 15 the dog causes the offset end 45 of the releasing arm 44 to engage the cam face 41 of the detent arm 40 and raises the latter, thereby causing the opposite arm of said lever to remove its shoulder 39 from engagement 20 with the actuating lever 30. The spring 35 thereupon swings the actuating lever about its pivot and causes the movable jaw 24 to be swung to open position. It will be noted that this opening movement of the clamping means occurs at the time the dog of the transfer is being raised into position to be struck by the bunter upon the lay and that, therefore, the clamping means are opened 25 before the lay reaches transferring position. 30 In the present invention means are provided for closing the clamping means immediately after transfer is effected and preferably while the filling carrier or bobbin is in flight from the shuttle to the box or container into which it is discharged. This is accomplished in the device illustrated in the accompanying drawings by a stud 46 which is carried by the transferrer arm and is so positioned that during the final transferring 35 movement of the transferrer arm the stud 46 will engage the offset end 47 of the lever 30 and swing said lever about its pivot in such a manner as to move the movable jaw to closed position and permit the detent 37 to 40 lock said lever in the manner heretofore described.

In the normal operation of the loom the jaws of the filling end clamping means are in closed position as illustrated in Fig. 3. 50 When transfer is called for the rotation of the controller rod 16 causes the arm 15 to raise the arm 14 on the shuttle feeler thereby acting, through the stud 13 upon the dog 11, to raise said dog in the path of the 55 bunter 12. As the dog 11 is thus raised the end portion 45 of the arm 44, which is carried by said dog, engages the cam face 41 of the arm 40 of the detent 37, raising the arm 40 and consequently depressing the other 60 arm of the lever, thus moving the shoulder 39 out of engagement with the end of the lever 30. As soon as this end of the lever is thus released the spring 35, acting upon the other arm of the lever 30, forces the 65 same forwardly or toward the front of the

loom thereby acting through the spring connection 27 to swing the movable jaw 24 of the filling end clamping means into the open position illustrated in Fig. 4. This action occurs before the lay reaches its 70 beat-up.

During the latter portion of the beat-up of the lay the bunter 12 carried by the lay engages the dog 11 of the transferrer and rocks the transferrer arm 6 about its pivot 75 in the usual manner, thus causing the transferrer head 7 to thrust a filling carrier or bobbin from the hopper into the shuttle, thereby ejecting the old filling carrier from the shuttle.

During the final portion of the transferring movement of the transferrer the stud 46, which is carried by the extension 9 of the transferrer, engages the offset end 47 of the lever 30 and moves the same forwardly, 80 thereby swinging the opposite end of the lever 30 rearwardly and causing the same, through the spring 27, to swing the movable jaw 24 into closed position.

It will be observed that the movable jaw 90 24 of the clamping means is thus swung across the path of the filling end running from the discharged filling carrier immediately after the filling carrier has been ejected from the shuttle so that the filling remains 95 under sufficient tension as it reels off of the filling carrier to enable it to be caught readily by the movable jaw of the clamping mechanism. Inasmuch as the movable jaw 24 is closed against the stationary jaw 23 before the completion of the transferring 100 movement of the transferrer the clamping of the filling end before the next pick of the shuttle is insured.

When the transferrer reaches the limit of 105 its movement the stud 46 will have swung the end of the lever 30 sufficiently to enable the shoulder 39 of the detent 37 again to engage the lever. The detent 37 is thus caused automatically to engage the lever by the action of the spring 42. By thus locking the lever 30 the filling end clamping means is 110 held in closed position until again released as above described upon a succeeding call for transfer.

It will be understood that the embodiment of the invention disclosed herein is illustrative and not restrictive and that various changes in construction and arrangement of parts may be made within the spirit and 120 scope of the following claims.

Having thus described my invention, what I claim as new, and desire to secure by Letters Patent, is:

1. In an automatic filling replenishing 125 loom comprising transferring mechanism and means for actuating the same, means for clamping the filling end from an ejected filling carrier, means operable upon the initial action of the transferring mechanism to 130

open said clamping means and means actuated by the transferring mechanism, during the final portion of its transferring movement, to close said filling end clamping means whereby the clamping of the filling end before the picking of the shuttle will be insured.

2. In an automatic filling replenishing loom comprising transferring mechanism and means for actuating the same, means for clamping the filling end from an ejected filling carrier, means for opening said clamping means, means operable by said transferring mechanism during the final portion of its transferring movement, to close said clamping means and means for locking said clamping means in closed position.

3. In an automatic filling replenishing loom comprising transferring mechanism and means for actuating the same, means for clamping the filling end from an ejected filling carrier, means for locking said filling end clamping means in closed position, means operable by the initial action of the transferring mechanism to unlock and open said clamping means and means actuated by the transferring means, during the final portion of its transferring movement, to close said filling end clamping means and to render effective the locking means.

4. In an automatic filling replenishing loom comprising a transferrer, a dog on said transferrer and means operable upon call for transfer to position said dog in the path of a bunter upon the lay, a filling end clamping means positioned in the path of the filling end from an ejected filling carrier, means operable by the movement of said dog into operative position to open said clamping means and means actuated by said transferrer, during its final transferring movement, to close said filling end clamping means upon the filling end.

5. In an automatic filling replenishing loom comprising a transferrer, a dog on said transferrer and means operable upon call for transfer to position said dog in the path

of a bunter upon the lay, a filling end clamping means positioned in the path of the filling end from an ejected filling carrier, means tending normally to open said clamping means, locking means for holding said clamping means in closed position, means operable by said dog, when moved to operative position, to release said locking means thereby permitting said clamping means to open and means actuated by said transferrer to close said clamping means and to render effective the locking means.

6. In an automatic filling replenishing loom comprising a transferrer, a dog on said transferrer and means operable upon call for transfer for positioning said dog in the path of a bunter upon the lay, a filling end clamping means comprising a stationary jaw and a movable jaw pivoted to swing across the path of the filling end of a discharged filling carrier, a lever connected to said movable jaw, resilient means engaging said lever tending normally to swing said jaw to open position, a detent for said lever acting to lock said jaw in closed position, means operable by the movement of said dog to operative position to release said detent and means carried by said transferrer adapted to engage and actuate said lever, during the final portion of the transferring movement, to close and lock said movable jaw.

7. In an automatic filling replenishing loom comprising a transferrer, a dog on said transferrer and means operable upon call for transfer for positioning said dog in the path of a bunter upon the lay, a stationary filling end clamping means comprising a stationary jaw and a movable jaw pivoted to swing across the path of the filling end of a discharged filling carrier, a movable jaw actuating lever, resilient means under tension connecting the same to said movable jaw and means operable by said transferrer for actuating said lever.

In testimony whereof, I have signed my name to this specification.

HENRY W. YOUNGQUIST.
